(57) **CLAIM**

The ornamental design for an automatic external defibrillator training device, as shown and described.

DESCRIPTION

FIG. 1 is a perspective top view of an automatic defibrillator training device showing the design;

FIG. 2 is a perspective bottom view of the automatic defibrillator training device of FIG. 1;

FIG. 3 is a side view of the automatic defibrillator training device;

FIG. 4 is a front end view of the automatic defibrillator training device;

FIG. 5 is a rear end view of the automatic defibrillator training device;

FIG. 6 is a top view of the automatic defibrillator training device of FIG. 1; and,

FIG. 7 is a bottom view of the automatic defibrillator training device of FIG. 1.

The broken lines are provided solely for illustrative purposes and form no part of the claimed design.
